(57) **CLAIM**

The ornamental design for a sensor cover package, as shown and described.

DESCRIPTION

FIG. 1 is a top plan view of a first sensor cover package, showing my new design;

FIG. 2 is a right-side elevational view thereof;

FIG. 3 is a back elevational view thereof;

FIG. 4 is a left side elevational view thereof;

FIG. 5 is a bottom plan view thereof;

FIG. 6 is a front elevational view thereof;

FIG. 7 is a perspective view of thereof;

FIG. 8 is a top plan view of a second sensor cover package, showing my new design;

FIG. 9 is a right-side elevational view thereof;

FIG. 10 is a back elevational view thereof;

FIG. 11 is a left side elevational view thereof;

FIG. 12 is a bottom plan view thereof;

FIG. 13 is a front elevational view thereof;

FIG. 14 is a perspective view of thereof;

FIG. 15 is a right-side elevational view for embodiments 3-7 thereof;

FIG. 16 is a back elevational view for embodiments 3-7 thereof;

FIG. 17 is a left side elevational view for embodiments 3-7 thereof;

FIG. 18 is a bottom plan view for embodiments 3-7 thereof;

FIG. 19 is a front elevational view for embodiments 3-7 thereof;

FIG. 20 is a top plan view a third sensor cover package, the other views being represented in FIGS. 15-19;

FIG. 21 is a top plan view a fourth sensor cover package, the other views being represented in FIGS. 15-19;

FIG. 22 is a top plan view an fifth sensor cover package, the other views being represented in FIGS. 15-19;

FIG. 23 is a top plan view a sixth sensor cover package, the other views being represented in FIGS. 15-19; and,

FIG. 24 is a top plan view of a seventh sensor cover package, the other views being represented in FIGS. 15-19.

The broken lines in the drawings are used to illustrate unclaimed environmental structure and form no part of the claimed design.

1 Claim, 11 Drawing Sheets
